UNITED STATES PATENT OFFICE.

BERTRAM C. KENYON, OF MISHAWAKA, INDIANA, ASSIGNOR OF ONE-HALF TO DODGE MANUFACTURING COMPANY, OF MISHAWAKA, INDIANA, A CORPORATION OF INDIANA.

TWO-CYCLE INTERNAL-COMBUSTION ENGINE.

1,215,383.

Specification of Letters Patent.

Patented Feb. 13, 1917.

Application filed March 9, 1914. Serial No. 823,623.

To all whom it may concern:

Be it known that I, BERTRAM C. KENYON, a citizen of the United States, residing at Mishawaka, in the county of St. Joseph and State of Indiana, have invented certain new and useful Improvements in Two-Cycle Internal-Combustion Engines, of which the following is a specification.

My invention relates to improvements in two-cycle internal combustion engines and it appertains more especially to the features pointed out in the annexed claims.

This type of power unit is also known as a two-stroke engine because it has a power stroke for each two movements of the pistons during one complete revolution of the crank shaft. The embodiment of these features in practice produces a much steadier turning movement than is possible with the well known "Otto" four cycle engine which has only one power stroke for every group of four strokes of the piston or every two complete revolutions. When in addition the construction comprises the use of two opposed cylinders and a double ended piston a power stroke becomes available for each stroke of the pistons or each one-half revolution of the shaft thus increasing the steadiness of action very materially over a single cylinder of the same type.

In addition engines of this type entirely dispense with timing gears and valves. Instead of these ports are formed in the cylinders to admit the power charges and also permit the exhaust gases to leave the cylinders. The cost of construction and the minimum number of actuating parts enables one to build this form of engine, more economically and with greater rapidity than similar engines have been made heretofore.

With these and correlated ends in view I illustrate in the accompanying drawings such instances of adaptation as will disclose the broad features of my invention without limiting myself to the specific details shown.

Figure 1. shows a side elevation in section.

Fig. 2. is a cross section on line $y-y$ of Fig. 1.

Fig. 3. is an end view showing parts broken away.

Fig. 4. is a lengthwise section on line $x-x$ of Fig. 3.

Fig. 5. is an elevation in section showing the crank disk recess.

Fig. 6. is an elevation of a crank disk and crank pin fastening.

Fig. 7. is a perspective of the one-part pistons and cross head slide.

In the drawings the location of the carbureter in Fig. 1 is diagrammatic. The bypasses of this figure and Figs. 2, 3 and 4 are also largely diagrammatic in their location relative to each other so as to avoid showing them crossing each other, it being understood that the best location is one that will secure the shortest and least obstructed passageways between the compression chamber and the working cylinders.

Two cylinders, 1 and 2 are cast with the usual water jacketing, an enlarged rectangular opening leading into the cylinder proper, inlet and outlet ports and the required bypasses. When these castings are joined so that the flanges 3 register with each other and suitable bolts 4 hold them together a large rectangular chamber is formed, one-half or the D portion in casting 2 and the other half or E portion in cylinder 1. Inlet chambers A and A' and exhaust openings B and B' are formed so as to be alternately uncovered by the pistons in their to and fro movement.

The cylinders have lugs 5 cast thereon by which they are secured to the chassis of an automobile or any other suitable base as desired, spark plugs 6 enter the cylinders at their outer ends and central of the cast-in heads. Inlet ports 7, arranged in pairs, lead into cylinders 1 and 2 from the chambers A and A' and exhaust ports 8, similarly arranged lead out of the cylinders into exhaust areas B and B'. These may be led into whatever arrangement of pipes, etc., desired. Cooling chambers 9 are cast around the working ends of the cylinders and annular recesses 10 and 10' are cast into the inner end of the cylinders so as to open into the compression spaces E and D. From recess 10' a by-pass 11 leads to inlet chamber A serving cylinder 1 and from recess 10 by-pass 12 leads to inlet chamber A' serving cylinder 2. The fuel intake is placed on the joining line between the two cylinder castings. It comprises the carbureter 13, check valve 14 and pipe 15. The piston casting combines, pistons 16 and a rectangular cross head frame 17. The pistons are hollow, having deflecting projections 18 cast on their working ends and the usual packing rings 19.

encircle them. The rectangular frame 17 serves as a compression piston, while sliding to and fro in chambers E and D, alternately sucking in fuel charges and compressing them ready for delivery to the working cylinders. The deflectors 18 may be cast as shown in Fig. 7 on an arc of a circle concentric with the piston, presenting a convex wall toward the inlet port, or in any other form desired.

Within the rectangular frame a cross head 20 slides transversely to the movement of the pistons. This may have any anti-friction lining and oiling arrangement desired. A crank pin 21 rotates within it. This pin may be forged solid with crank disk 22 and shaft 23, while disk 24 may be forged solid with shaft 25. The crank pin 21 is tapered at 26 where it enters a corresponding hole of the disk 24 and to which it is secured by a pin 27. To assist in keeping the disks central concentric bosses 28 are formed. These rotate in corresponding recesses formed in the engine castings. Shafts 23 and 25 have bearing in projections 29 cast half and half in the main castings. In addition the disks 22 and 24 fit into annular recesses so as to "seal in" the movement of the compressing frame 17 and prevent the compression leaking from the recesses 10 and 10' onto the opposite side of 17 through the space occupied by the disks 22 and 24. This is accomplished by casting a wall 30 at four points opposite the vertical diameters of disks 22 and 24 thus sealing off chambers 10 and 10', as shown in Fig. 4.

The rectangular compression chamber E—D in which the supplemental "piston" 17 slides serves a double purpose, by forming a means for compressing the working charges and at the same time preventing the pistons turning on their axes, thus avoiding the use of inefficient splines or other makeshifts to prevent twisting strains and friction between the crank pin and driving attachment to the pistons.

The procession of operation may be described as follows. Air and fuel are sucked past the check valve into chambers E and D on the out stroke of pistons into cylinder 1 which on their return stroke toward cylinder 2 is compressed in space D and recess 10'. Just as soon as this stroke has ended the compressed charge will rush through by-pass 11, chamber A and ports 7 into cylinder 1 where it is further compressed as the piston again moves into this cylinder. When at the end of this stroke the charge is ignited and the pistons are sent toward cylinder 2, repeating the operation. As the piston moved into cylinder 1 the charge contained in chamber E was compressed and forced into recess 10 from which it rushed through by-pass 12 into cylinder 2, to be further compressed on the power

stroke emanating from cylinder 1, thus being gotten ready for its ignition as the stroke ends, again pushing the pistons toward cylinder 1 and repeating the operation. The exhaust occurs as the pistons reach the end of the power stroke by reason of ports 8 being uncovered by the pistons in alternate order. The inrushing charges are deflected by projections 18 toward the ends of the cylinders from which they recure and drive out the products of combustion of the previous explosion but their progress through the exhaust ports 8 is arrested on the first portion of the out stroke of the pistons.

When engines of this type are used for automobile service they may be placed transversely of the chassis to advantage, as then it is a simple matter to connect the driving shaft to the crank shaft by a suitable clutch, one part of which may be formed in the fly wheel. From the foregoing description it will be seen that engines built to my novel type are as simple as possible to make and likewise free from complexity of operation. Engines of the two stroke type have heretofore been made with separate pistons, tie rods, connecting rods, bar cranks, stuffing boxes, roller cranks, splines, gudgeon pins, perforate pistons, etc., all of which parts are omitted in my engine hence its simplicity is quite obvious.

What I claim is,

1. In internal combustion engines, a pair of pistons integrally formed with each other having an enlarged transverse rectangular frame serving as a compressor therebetween whose walls in one plane are approximately the same as the piston diameter and in a plane perpendicular thereto project radially from the pistons forming a rectangular space within the walls with open sides thereto, a suitable casing for the pistons having walls which inclose separate cylinders and preliminary compression chambers the latter being rectangular to conform to the shape of the compressor frame forming a guide for such frame and at the same time closing the open sides of the frame, inlet and outlet ports to the cylinders, separate passage-ways connecting from the compressing chambers to the inlet ports of opposite cylinders, whereby as the pistons move to and fro flow is established in the passage ways in alternate sequence.

2. In internal combustion engines, a pair of oppositely placed interconnected cylinders, an enlarged rectangular chamber between them inclosed by their connecting walls, an integrally formed power unit comprising an open sided rectangular frame between the two pistons the pistons and frame being simultaneously movable respectively in the cylinders and said chamber, a crank shaft, crank disks thereon, recesses in the walls of the enlarged chamber for said disks,

a crank pin connecting the disks, a movable member on said pin, means for operatively connecting the member and the frame of the power unit, and means embodying the 5 walls of the enlarged chamber and the disks for closing the open sides of the frame.

3. In internal combustion engines, a two-part casting comprising a rectangular portion forming a compression chamber one- 10 half in each part, a cylinder in each part connecting with the chamber, a supplemental enlarged annular chamber between each cylinder and the compression chamber, suitable bearings transverse of such chamber, 15 circular recesses formed on the inner walls of the chamber concentric with the bearings, crank disks in such recesses, a crank pin joining the disks, suitable shafts extending into the bearings from the disks, 20 a one-piece reciprocating member comprising two power pistons slideable in the cylinders aforesaid and an open sided rectangular frame movable in the compression chamber between the cylinders its open sides being closed by the crank disks and the side 25

walls of the chamber, a cross head on the crank pin and slideable within the rectangular frame, and suitable passage ways from the supplementary annular chambers to the opposite cylinders.

4. A double ended piston, a rectangular frame cast integrally with said piston the walls of which are adapted to serve as supplemental pistons, a rectangular two-part chamber inclosing said walls, separate cylinders cast integrally with the chamber walls, a sliding block within the rectangular frame, circular recesses within the chamber walls, crank disks rotatable in said recesses, a crank pin passing through the sliding block and connected to each crank disk, shaft extensions to the disks, and suitable ducts or passage ways leading between the cylinders and the rectangular chambers.

In testimony whereof I affix my signature in presence of two witnesses.
